UNITED STATES PATENT OFFICE.

OVERTON WINSTON, OF MINNEAPOLIS, MINNESOTA.

HEADLIGHT.

1,349,595.

Specification of Letters Patent. Patented Aug. 17, 1920.

Application filed March 2, 1917. Serial No. 151,931.

To all whom it may concern:

Be it known that I, OVERTON WINSTON, a citizen of the United States, residing at Minneapolis, in the county of Hennepin 5 and State of Minnesota, have invented certain new and useful Improvements in Headlights; and I do hereby declare the following to be a full, clear, and exact description of the invention, such as will enable others skilled in the art to which it 10 pertains to make and use the same.

My present invention relates to headlights and is particularly directed to the provision of an improved form of lens and 15 to an improved relative arrangement thereof, in respect to a concave reflector and electric light source within the latter.

In the accompanying drawings which 20 illustrate the invention, like characters indicate like parts throughout the several views.

Referring to the drawings:

Figure 1 is a vertical section showing a 25 headlight embodying my invention and wherein a two-filament light bulb is employed as a means for shifting the light source from the axis of the reflector to a point vertically above said axis;

Fig. 2 is an elevation looking at the inner 30 face of the lens;

Fig. 3 is a fragmentary view in inner 35 face elevation showing, on an enlarged scale, one of the prismatic sections of the lens;

Fig. 4 is a section on line 4—4 of Fig. 3; 40 Figs. 5, 6 and 7 are transverse sections taken on the lines 5—5, 6—6, and 7—7 of Fig. 3;

Fig. 6* is an enlargement of the prism 45 shown in Fig. 6, but indicating the travel 40 of the ray of light in passing thereto, therethrough and therefrom; and

Fig. 8 is a view corresponding to Fig. 1, but showing a headlight having a single 50 filament light bulb.

Of the parts of the headlight, the numeral 55 9 indicates the casing, the numeral 10, the clamping ring thereof, the numeral 11 the concave reflector, the numeral 12 the electric light bulb and the numeral 13 the lens.

The reflector 11 is preferably a hyperbolic 60 reflector and it is provided with an axial passage through which the shank of the light bulb 12 projects and is held by a suitable support. This bulb support, so far as 65

this invention is concerned may be of any 70 suitable construction, but as shown, com-

prises a shank engaging sleeve 14 and a tubular socket 15 screwed into a flanged hub 16 secured to the back of the reflector.

The bulb shown in Fig. 1 is a two-filament bulb the one filament having its hot spot at *a* and the other having its hot spot at *b*. The point *a* is at the axis of the reflector and preferably also at the focal center thereof. The point *b* is vertically above 60 the axis of the reflector. By means of a three-lead circuit 17, 18, and 19, which includes a battery 20, and switches 21 and 22, either of the two filaments *a* and *b* may, 65 at will, be energized and used as the light 70 source of the headlight. These electric connections are more fully disclosed in my pending application S. N. 86,852, filed of date March 27, 1916, and entitled "Headlights."

In the headlight illustrated in Fig. 8, the light bulb 12 is provided with a single filament *c*, the hot spot of which is at the axis 75 of the reflector and preferably also at the focal center thereof. This filament is connected to a battery or source of electrical energy 23, by leads 24 in one of which is a switch 25.

We will now consider the novel construction of the lens, the preferred form of 80 which is illustrated in the drawings and which, described in detail is as follows:

One face of the lens, preferably its inner 85 face, is formed with prismatic surfaces that extend horizontally across that face of the lens. The beveled surface of all of the prisms diverges downwardly from the plane of the lens, but the different prisms have a different bevel. The greatest bevel is approximately at a horizontal line that intersects the axis of the lens and headlight, and in the lens illustrated, the said horizontal prism that intersects said axis has a downward divergence or bevel of eighteen degrees to the plane of the lens. The bevel 90 of the successive prisms in directions both vertically upward and vertically downward from the said horizontal line or plane of the axis of the lens, progressively decreases, preferably, in a constant order of 95 succession. For example, the variation in the bevel of successive prisms may be, as indicated by the small numerals marked adjacent to the right hand extremities thereof on Fig. 2 by reference to which it will 100 be noted that the uppermost and lowermost prisms have a bevel of only one-half degree 105

to the plane of the lens, and the bevel of the upper prisms increases one-half degree, each over the other to the horizontal plane of the axis of the lens, while the prisms that are 5 below said horizontal plane progressively increase in like manner in an upward direction.

Each particular prism, in a horizontal direction, preferably has a constant bevel. 10 For example, if it has an angle of eighteen degrees at the axis of the lens, it will have the same bevel at its extremities, or at the margin of the lens, but in some instances the angle in each particular prism may vary 15 in a horizontal direction, as for example, in my companion application filed of date March 3rd, 1917, S. N. 152,228, and entitled "Headlights."

By reference to Fig. 6^a, it will be noted 20 that a ray of light in passing through one of the prisms, will be given a downward deflection. This, of course has the general effect of producing a downward deflection of the light beam. In view of the increasing 25 bevel of the prisms nearest to the horizontal plane of the axis of the reflector it is obvious that the greatest downward deflection will be given to the most intense light rays that come from the back of the reflector. 30 This, of course, is desired in order to throw the greater part of the light onto the road.

In Fig. 1, the lighter ray lines indicate the light rays when the light source is at *a* and the heavier ray lines, the rays when the light 35 source is at *b*; and it will be observed that the beam is given greater downward deflection when the light source is at *b* than when the light source is at *a*. This is especially true in respect to the more intense rays from 40 the back of the reflector, and in fact, some of the extreme upper and lower rays will be slightly higher when the light source is at *b* than when the light source is at *a*.

Obviously, the best light beam for country road driving is produced when the light 45 source is at *a* and the best light beam for city street driving is produced when the light source is at *b*. It is not desirable to give this great downward deflection to the less intense rays from the upper portion of 50 the reflector as is given to the more intense rays from the back of the reflector. It is desirable to get a maximum amount of intense rays on the road, but it is also desirable 55 to diffuse some of the less intense light rays so as to light up objects above the road and at the sides of the road, and for this reason, the prisms nearest to the horizontal plane of the axis of the reflector are given greatest 60 bevel and those nearest the top and preferably also those nearest the bottom are given decreased or less angle.

In the use of a headlight with an ordinary reflector adjusted so as to throw approximately the lower half of the light beam upon

the ground, which is quite a common arrangement, the lower half of the light beam will be distributed over many hundreds of square feet of road surface, and per unit of surface, the road will be given but a very 70 small percentage of light as compared with the amount of light thrown upon a vertical object in the road, by the upper half of the light beam. This is a result just reverse from that desired. An ideal arrangement 75 would be one in which there would be at least as much light, per unit of surface, thrown upon the road as there would be upon a vertical object above the road; and such an arrangement, obviously, requires very much 80 the greater part of the light beam to be distributed on the ground and a very minor part of the light beam to be diffused above the road. This ideal result is closely approximated by the use of the improved lens 85 above described, which, as already stated, produces very great downward deflection of the more intense rays of the light beam and diffuses some, or a minor part, of the less intense light rays above the road. 90

It is important to note that, in the applicant's lens, the reverse progression from an intermediate prism, in the order of succession, is the same in all planes that intersect the several prisms at a right angle. For instance, in the lens shown in the drawings, the order of succession of the progression is step by step from the one prism to the other, and this same order is present in all of the vertical cross sections through the lens. 100

What I claim is:

1. A lens for headlights having parallel prisms beveled in the same general direction, said prisms having, in respect to the basal surface of the lens, bevels, the angles of 105 which, as among the successively adjacent prisms, decrease, step by step, in reverse order, in opposite directions from an intermediate prism located at the diameter of the lens. 110

2. A lens for headlights having parallel prisms beveled in the same general direction, said prisms having, in respect to the basal surface of the lens, bevels, the angles of which, as among the successively adjacent 115 prisms, decrease, step by step, in reverse order, in opposite directions from an intermediate prism, located at the diameter of the lens, each individual prism having substantially the same bevel in all of its cross sections. 120

3. A lens for headlights having parallel prisms beveled in the same general direction, said prisms having, in respect to the basal surface of the lens, bevels, the angles of 125 which, as among the successively adjacent prisms, decrease, step by step, in reverse order, in opposite directions from an intermediate prism, located at the diameter of the lens, the prisms that are equidistant from 130

said intermediate prism, having the same angle to the basal surface of the lens.

4. A lens for headlights having parallel prisms beveled in the same general direction, 5 said prisms having, in respect to the basal surface of the lens, bevels, the angles of which, as among the successively adjacent prisms, decrease, step by step, in reverse order, in opposite directions from an intermediate, 10 diate prism, located at the diameter of the lens, each individual prism having substan-

tially the same bevel in all of its cross sections, the prisms that are equidistant from said intermediate prism, having the same angle to the basal surface of the lens.

15

In testimony whereof I affix my signature in presence of two witnesses.

OVERTON WINSTON.
